UNITED STATES PATENT OFFICE

FRANK WOLF, OF NEW YORK, N. Y.

HOLDER FOR COLLAPSIBLE TUBES

Application filed January 18, 1928. Serial No. 247,501.

This invention relates to improvements in holders for collapsible tubes, and has particular reference to such devices which will be portable and capable of supporting collapsible tubes in upright position and accessible for manual extrusion of the contents.

An important object of the invention in its broader aspects, is to provide a tube holder which will support the tube by virtue of a clamping action upon a relatively narrow portion thereof and preferably adjacent its outlet end.

Another object of the invention is to provide such a device with novel and simplified means for effecting the clamping relation.

Another object is to provide a tube holder of the above mentioned character with a service cover which may readily be applied to or removed from the stand.

With the foregoing and other objects and advantages in view, the invention resides in the novel details of construction, combination and arrangement of parts hereinafter set forth, shown by way of illustration in the accompanying drawings and specifically pointed out in the appended claims.

In the drawings wherein similar reference characters designate corresponding parts throughout the several views—

Figure 1 is a front elevation of one form of tube holder embodying the invention,

Fig. 2 is a side elevation thereof with the parts in tube clamping position and with the service cover disposed in its opened position,

Fig. 3 is a view similar to Fig. 2, but showing the tube clamping means unlocked,

Fig. 4 is a fragmentary vertical transverse sectional view on line 4—4 of Fig. 1,

Fig. 5 is a horizontal sectional view on line 5—5 of Fig. 2,

Fig. 6 is a top plan view with the parts in the positions shown in Fig. 3,

Fig. 7 is a fragmentary vertical sectional view on line 7—7 of Fig. 2,

Fig. 8 is a front elevation of a modified form of tube holding stand,

Fig. 9 is a side elevation thereof,

Fig. 10 is another side elevation, showing the parts in unlocked position,

Fig. 11 is a vertical transverse sectional view on line 11—11 of Fig. 9,

Fig. 12 is a horizontal sectional view on line 12—12 of Fig. 9, and

Fig. 13 is a vertical transverse sectional view on line 13—13 of Fig. 10.

The embodiment of the invention illustrated in Figs. 1 to 6 inclusive, is in the nature of a stand which is formed from a pair of relatively movable members 10 and 11, each of which may be conveniently formed from sheet metal or the like and adapted to firmly clamp and support the collapsible tube 12. The member 10 comprises a pair of upwardly extending side portions 13, which are spaced apart and adapted to be disposed at opposite sides of the tube 12; said portions having laterally offset curved gripping members 14, which are adapted to jointly embrace the upper portion of the tube 12. The lower ends of said side portions 13 are flared outwardly, as indicated at 15 and connected together by a transverse strip 16, which may preferably be integral with the side members, and which in combination with the flared portions 15, comprise a supporting base for the device. The member 11 is similarly formed with spaced side portions 17, the lower ends of which are disposed in substantially the same planes as the side members 13, while their upper ends are deflected out of said plane, whereby to be capable of relative movement over the same, as clearly shown in Fig. 3. Gripping members 18, similar in all respects to the members 14, are carried by the upper extremities of said side members 17, while their lower ends are flared as at 20 and connected together by a transverse strip 21 in a manner similar to the base portions 15 and 16 of the member 10. Intermediate their ends, said side portions 13 and 17 are provided with semi-circular extensions 22 and 23 which overlap and are formed with aligned openings to accommodate pivot pins 24 about the axis of which the members 10 and 11 are adapted to be moved.

The opposing edges of the flared portions 15 and 20 are provided with notches 25 and

26 respectively, which cooperate to form openings in the stand for the reception of the outer ends of the base strip 27 of the tube 12, and preferably, in such a manner 5 as to engage the same with a clamping pressure. Preferably, the longitudinal edges of the side portions 13 and 17 are tapered in such a manner as to converge upwardly, as indicated at 28 and 29, and slidable actuating means 30 are mounted upon said members for the purpose of selectively locking or unlocking the parts with reference to the tube. The body of said actuating means 30 may be conveniently formed of sheet material 15 which extends transversely across the outer faces of said portions 13 and 17 and having its opposite ends reversely bent, as indicated at 31 and 32 to straddle the tapered edges 28 and 29 and to engage the inner surfaces of said portions 13 and 17. Preferably, curved finger pieces 33 are secured to the actuating means 30 in such a manner as to facilitate their manipulation.

In order to secure the collapsible tube 23 within the novel holder above described, it is only necessary to relatively move the members 10 and 11 to the positions shown in Fig. 3, whereupon the tube 12 can easily be inserted in an endwise relation upwardly 20 through the base thereof, after which the actuating means 30 can be moved downwardly, causing the gripping members 14 and 18 to engage the upper portions of the tube walls immediately below the outlet end thereof, 25 and at the same time to engage the base strip 27 within the cooperating notches 25 and 26. The gripping members 14 and 18 are so proportioned that they will actually deflect the engaged portions of the tube wall 30 in such a manner as to form grooves therein, as indicated at 34, and by virtue of this arrangement, it will be evident that the tube will be firmly held and incapable of accidental displacement from the holder.

45 An annular frame member 35 is provided for the upper end of the holder; said frame member being suitably formed with a central aperture 36, through which the threaded neck 37 of the tube is adapted to extend, 40 and being further characterized by a depending rim or skirt portion 38 which encircles the members 14 and 18 and frictionally engages them in such a manner as to assist in maintaining them in their tube 45 clamping positions. Carried by said frame member or head 35, is a closure cap 39, which is preferably pivoted as at 40 and adapted to overlie the threaded extremity 37 of the tube, whereby to cover the same. A suitable spring 41 may preferably be provided to engage a projection 42 on the outer side of the cover 39 in such a manner as to securely hold the said cover in closed position.

65 From the foregoing, it will be evident that

a novel holder for a collapsible tube has been provided in the nature of a portable stand, which firmly grips the tube and maintains it in position for easy use. Incidentally, the service cover 39 does away with the necessity for using the inconvenient screw threaded cap with which such tubes are provided by the manufacturers. The material from which the parts are made can be nickel plated, enameled, or otherwise finished, whereby to enhance the appearance of the device, and all of these features taken together constitute a substantial advance in the art.

A modified form of the invention has been shown in Figs. 8 to 13 inclusive, wherein the tube supporting stand is formed from rod stock as distinguished from sheet material. Such a stand comprises a pair of spaced upright members 45 and 46 at each side of the device; said members being connected together adjacent their upper ends by a loop 47, and being provided at their lower ends with off set portions 48 and 49 extending in opposite directions and constituting a base for the stand. The loop 47 provides suitable resiliency, whereby the upright members 45 and 46 are capable of relative movement toward and away from each other, and such movement is controlled by a slide 48, which is similar in structure and function to the actuating member 30, described in the first embodiment. Secured to the upper sides of the loops 47 are a pair of spring arms 50, the upper ends of which are suitably curved to constitute tube gripping members 51. Furthermore, the structure may be reinforced by means of a ring 52, which is rigidly secured to the loops 47 and the spring arms 50 in such a manner as to maintain said loops in proper spacing with respect to each other. The resiliency of the arms 50 and gripping members 51 is such that as the tube 12 is inserted with the parts shown in the positions of Fig. 10, the upper end of said tube will be automatically engaged by said gripping members 51, and thereafter, the slides 48 can be moved downwardly to effect the clamping engagement of the members 45 and 46 on the opposite sides of the bottom strip 27 of the tube.

While the tube will be properly supported in an upright position by the stand as just described, it is preferable to employ the frame member 35 and closure cap 39; said frame member being disposed upon the upper end of the stand and frictionally engaging the tube clamping members 51 in a manner similar to its coaction with the members 14 and 18 of the first embodiment. Furthermore, it will be evident that said frame member 35 and its associated service cover may be so formed as to frictionally engage upon the outer surface of the tube,

irrespective of whether the tube is mounted in a supporting stand or not.

5 The head with the cover 35 thereon can of course, be used without the stand if desired. The invention is susceptible of numerous further modifications in the details of construction and arrangement of parts, and the right is therefore reserved to make such changes as fall within the scope of the 10 appended claims without departing from the spirit of the invention.

Having thus described my invention, what I claim is:—

1. In a holder for collapsible tubes, a 15 stand having upright members movable toward and away from each other, said upright members being adapted to engage the laterally projecting end portions of the tube base, means at the upper end of the stand 20 for clamping a relatively narrow portion of the tube adjacent its outlet end, and means slidable on said upright members for locking the same in clamping position with reference to the tube.

25 2. In a holder for collapsible tubes, a stand having upright members movable toward and away from each other, said upright members being adapted to engage the laterally projecting end portions of the tube 30 base, means at the upper end of the stand for clamping a relatively narrow portion of the tube adjacent its outlet end, means slid- 35 able on said upright members for locking the same in clamping position with reference to the tube, and a closure for the top of the tube adapted to embrace and reinforce said clamping means.

3. In a holder for collapsible tubes, a 40 stand having upright members movable toward and away from each other, said upright members being adapted to engage the laterally projecting end portions of the tube base, means at the upper end of the stand 45 for embracing and clamping a relatively narrow portion of the tube adjacent its outlet end, and means slidable on said upright members longitudinally thereof from one 50 position to another to have a clamping action thereon for locking the same in clamping position with reference to the tube.

4. In a holder for collapsible tubes, a stand having upright members movable toward and away from each other, said upright members being adapted to engage the 55 laterally projecting end portions of the tube base, means at the upper end of the stand for embracing and clamping a relatively narrow portion of the tube adjacent its outlet end, means slidable on said upright members longitudinally thereof from one 60 position to another to have a clamping action thereon for locking the same in clamping position with reference to the tube, and an 65 annular member encircling and frictionally

engaging said tube clamping means to hold the same against accidental displacement.

5. In a holder for collapsible tubes, a stand having upright members movable toward and away from each other, said upright members being adapted to engage the laterally projecting end portions of the tube base, means at the upper end of the stand 70 for embracing and clamping a relatively narrow portion of the tube adjacent its outlet end, means slidable on said upright members longitudinally thereof from one position to another to have a clamping action thereon for locking the same in clamping position with reference to the tube, an annular member encircling and frictionally 75 engaging said tube clamping means to hold the same against accidental displacement, and a service cover hingedly mounted on said annular member and adapted to form a closure for the outlet end of the tube.

6. In a holder for collapsible tubes, the combination of connected stand members movable from open to closed position, means at the upper ends of the members adapted, in 80 the closed position thereof, to embrace and clamp the tube adjacent its outlet end, to thereby support the tube with its outlet end uppermost, an annular member for holding 85 said embracing and clamping means against accidental displacement, and a service cover for the outlet end of the tube connected to said annular member.

7. In a holder for collapsible tubes, the combination of connected stand members 90 movable from open to closed position, means at the upper ends of the members adapted, in the closed position thereof, to embrace and clamp the tube adjacent its outlet end, whereby to support the tube pendant from 95 the upper ends of the members and with its outlet end uppermost, an annular frame member for engaging said embracing and clamping means to retain the same against displacement, and a service cover hinged to 100 said frame member and adapted to selectively cover or uncover the outlet end of the tube.

8. In a holder for collapsible tubes, the combination of connected stand members 105 movable from open to closed position, arms on the upper ends of the members adapted, in the closed position thereof, to embrace and clamp the tube adjacent its outlet end, whereby to support the tube pendant from 110 the upper ends of the members and with its outlet end uppermost, an annular frame member for engaging over said arms to maintain them in clamping relation, and a service cover pivotally mounted on said 115 frame member.

9. A holder for collapsible tubes comprising relatively movable members each of which comprises longitudinally extending side portions, the side portions of one mem- 120 125 130

ber being connected to the side portions of the other, said members supporting parts for gripping the exterior of the tube, and means 5 slideable along the adjacent side portions for securing said members in a position of adjustment.

10. A holder for collapsible tubes according to claim 9, in combination with a hollow head for the end of the tube, said head 10 having a portion to engage the parts for gripping the exterior of the tube and hold them in operative position.

11. A holder for supporting a collapsible tube having a relatively rigid top end and a 15 collapsible body joining the top end, the holder being arranged to support the tube in upright position with its rigid top end uppermost, said holder comprising upright members, and lateral arms on the top ends 20 of the upright members adapted to press into the collapsible body at a point in which said rigid top end will rest upon said arms, whereby to support the tube in hanging position through the engagement of said rigid 25 top end over and upon said lateral arms.

12. A holder for a collapsible tube having a relatively rigid top end and a collapsible body joining the top end, the holder being arranged to support the tube in upright position 30 with its rigid top end uppermost, said holder comprising upright members, and lateral arms on the top ends of the upright members adapted to press into the collapsible body immediately adjoining the 35 said relatively rigid top end so as to engage underneath said rigid top end, whereby to afford a support for the tube through the engagement of said rigid top end upon said lateral arms, and a closure for the top end 40 of the tube adapted to embrace and reinforce said lateral arms.

In testimony that I claim the foregoing as my invention, I have signed my name hereto.

FRANK WOLF.
